UNITED STATES PATENT OFFICE

2,527,039

THERAPEUTIC UNIT

Hugo R. Swanson, Binghamton, N. Y.

Application June 14, 1948, Serial No. 32,843

4 Claims. (Cl. 128—373)

1

This invention relates to improvements in heat treating and massaging cabinets adapted to efficiently effect all of the treatments and manipulations common to such devices.

The general object of this invention is to provide in a complete unit a mechanism of this type by means of which the body of a person may be subjected to heated vapors having, or not having, as required therapeutic values and circulated in a manner to insure the comfort of the person while attaining the desired treatment thereof.

Another object of the invention is to provide in combination in such a unit all of the usual appurtenances by means of which a person may be completely treated, including a power supply for massaging implement, hot and cold water sprays, and the like.

A more specific object of this invention is to provide a combination of instrumentalities of this type particularly adapted to the efficient and proper treatment of a patient.

The actual details of the mechanism comprising this invention will best be understood by the following detailed description of the embodiment thereof illustrated in the attached drawings.

In the accompanying drawings,

Figure 1 is a side elevational view of the unit of this invention showing some parts broken away to better illustrate details thereof;

Figure 2 is a view similar to Figure 1, showing the cabinet doors open to show the interior construction with some of the exterior mechanism omitted;

Figure 3 is a righthand elevational view of the unit;

Figure 4 is a somewhat diagrammatic and top plan view of the interior of the cabinet;

Figure 5 is a side elevational view with some parts broken away of the platform or table on which the person being treated lies within the cabinet;

Figure 6 is a lefthand elevational view of the unit with some of the bottom structure broken away;

Figure 7 is an enlarged side elevational view of the lefthand end of the cabinet from the front showing the details of construction of the vertically slidable door at that end;

Figure 8 is a horizontal cross-sectional view at an edge of the door showing how it is slidably mounted, taken on the line 8—8 of Figure 6;

Figure 9 is a cross-sectional view taken on the line 9—9 of Figure 8;

Figure 10 is a detailed view showing some parts in cross section illustrating the mounting of the

2

platform tray and the construction of the bottom of the cabinet;

Figure 11 is an elevational view of the air and vapor exhaust container and trap;

Figure 12 is a top plan view thereof;

Figure 13 is an elevational view of the container for the liquids to be vaporized and admixed with air for introduction into the cabinet;

Figure 14 is a top plan view thereof;

Figure 15 is a top plan view of the heater unit for the cabinet; and

Figure 16 is a cross-sectional view taken on the line 16—16 of Figure 1.

The complete unit is mounted upon a framework of any suitable construction, not shown, having the four legs or standards 1 at the four corners thereof. Longitudinal trim and bracing strips 2 extend between the front and back legs in pairs and the transverse trim and bracing strips 3 extend between the front and back legs in pairs (see Fig. 3). As will be seen from Figures 3 and 6, the cabinet comprises the righthand wall 180 and the lefthand wall 4. The bottom wall 5 of the cabinet comprises a pair of flatly inclined converging wall sections united by a narrow horizontal section, possibly best seen in Figure 10. As shown in Figure 6, the cabinet is provided with a back wall 6, which is preferably lined with a layer of suitable insulating material 7. The front wall 8 of the cabinet consists of a door 10 mounted by means of a hinge 11 upon a front wall strip 20 which may consist of a separate strip secured in place or consist of a flanged extension of the bottom wall 5 (see Fig. 10). The front side edges 35 of the cabinet are formed by a pair of strips 8 which are provided with flanged lips 8' (see Figs. 1 and 16) which form rectangular seats in which the side edges of the door 10 lie when it is closed, so as to form a flush surface. The top of the cabinet is closed by means of a door 9 hinged at 19 (see Fig. 6) and having a recess along its free edge (see Fig. 16) formed by the flange 9' to match up with the flanged recess formed by the flange 8' so that the top edge of the side door 10 may lie flush with the end edge of the top door 9. The doors 9 and 10 are preferably convex both longitudinally and transversely, as illustrated in the drawings to give a pleasing appearance to the cabinet.

As shown in Figure 1, the front door 10 is provided with a handle 10' for manipulating it and a series of catches 12 of any suitable form for locking the doors 9 and 10 closed. The top door 9 is provided with a handle 14 for manipulating it and has mounted thereon, as shown a ther-

mometer 13 for indicating the temperature within the cabinet. Both doors 9 and 10 are held in closed position by means of spring structures clearly shown in Figures 3 and 4 respectively. The spring structure for the top door 9 comprises a tube 15 pivotally mounted on the top of the cabinet at one end in which a spring 16 is anchored at one end and connected by a cable 17 to an anchor 18 at the back of the cabinet at the top. Similarly (see Fig. 4) the front door 10 is connected by means of a cable 8^a to a spring 8^d anchored at its other end within a tube 8^c. The tubes 15 and 8^c are preferably pivotally mounted at their far ends to permit light swinging movement as the doors are opened and closed. These spring structures insure that a tight vapor seal is formed when the doors are in closed position. This seal is further insured by means of the latching devices 12 (see Fig. 1) which may be of a type to draw the adjacent door edges tightly together so as to cause the door 10' to seat on the flanges 8' and 9'.

Referring to Figures 6 to 9 inclusive, it will be seen that the end wall 19 is provided with a large rectangular opening 4' in the sides of which are mounted a pair of guide members 21 triangular shaped in elevation and L-shaped in cross-section (see Fig. 8). Secured to the inner inclined flanged edge of the members 21 is an L-shaped strip 21' to provide guiding grooves for the side edges of a door 22 preferably made of transparent material. The lower edge of the door 22 is cut out in substantially semicircular form as appears in Figure 6, so that the door may be closed around the neck of the person being treated, as shown in Figure 1, to form a vapor seal. The complete peripheral edge of the door is enclosed within a reinforcing trim strip 22' of any suitable material, as clearly indicated. A bar 22'' is mounted on the outer face of the door on which a towel may be hung so that it can be draped about the person's neck. The frame 22' includes a relatively wider section at the top, as shown at 22^a (see Fig. 9) which is provided with an opening in which a door 23 may slide horizontally.

Thus it will be seen that a vaportight cabinet is formed when the doors are all closed and the person is in proper position. As indicated at 7 in Figure 6, if desired the top wall, including the door 9 and the front wall including the door 10 can be lined with a layer of heat insulating material.

As is clear from Figure 10, the interior of the cabinet near the tapered bottom wall 5 is provided with a frame or supporting members 31 on which a tray or plate form 30 mounted with suitable bracing struts 32 may be mounted in a plane at about the level of the hinge 11. As shown in Figures 4 and 5 the bottom wall 30^b of the body support tray 30 inclines from the left to the righthand end and is provided at its lower end with a series of moisture drain holes 30^c. The bottom wall is also provided with a series of larger air passage apertures 30^a, and the narrow side walls of the platform may be provided with a series of air or ventilating apertures 30^d. A mattress M (see Fig. 5) of suitable material may rest on the bottom wall 30^b and is provided with apertures to register with the apertures 30^a to admit air and vapor circulation. A moisture drain connection including a trap is shown at 33 extending from the low point of the bottom wall 5 to a point exterior of the wall 34 so that a connection to waste may be made when the machine is installed.

The wall 34 is part of a compartment (see Fig. 1) below the cabinet, which is provided with doors at the front and back, of which the front doors 35 and 36 are shown. These doors are locked in closed position by means of suitable catches 37 and 38. A compartment thus formed provides a storage place for the various auxiliaries and accessories used with such machines and mounted in any suitable manner as by means of hinges, not shown.

In the compartment closed by the door 36 is an electric motor 38 which is connected by means of a speed reduction gear 39 to an output shaft 40 to which a flexible shaft 43 may be attached.

15 This flexible shaft issues from the compartment through a slot 41 (see Fig. 3) and enters the cabinet through an aperture 42. It is supported by means of a spring 45 depending from a sleeve 46 slidably mounted on a shaft 47 extending lengthwise of the cabinet at the top. 20 When not in use the flexible shaft rests on the brackets 44 on the back wall 6 of the cabinet. Various implements may be connected to this flexible shaft for muscle and flesh manipulation, as is well known in the art, and as represented for example by means of the massaging implement disclosed in my copending application Serial No. 23,848, filed April 8, 1948.

Also in the same compartment is another electric motor 48 which is connected to a blower 49, the discharge port of which is connected by a pipe 50 (see Fig. 3) to a conduit 51 which opens into the bottom of a cabinet 45 having the hinged door 46 by means of which it can be closed. The inlet port of the blower is connected by a conduit 55 and a branch 53 to the interior of the cabinet below the body supporting platform (see Fig. 1). The conduit 51 is provided with a branch 54 which extends to a moisture and vapor receptacle 56 (see Figs. 11 and 12) which is closed at the top by means of a funnel-shaped member 57 having an opening to the atmosphere. The conduit 54 connects tangentially with the container 56 and includes a flap valve 55 actuated by suitable levers and a link 58. As shown in Figure 3, the link 58 extends to the top of the cabinet and is provided with an operating crank 59.

The bottom wall 60^a of the cabinet 45 (see Fig. 3) comprises an open framework (see Fig. 15) having a series of vertically extending holes 60^b therein. The discharge end of duct 51 is attached to the bottom wall so that the air and vapors are discharged into the compartment 45 through the aperture 60^c and the opening formed by the framework 60^a. Supported in the framework is an electrical heating unit 61 positioned below a rack or receptacle 60 adapted to receive a container 62. As shown in Figure 13, this container 62 is partially closed at the upper end by means of the funnel-shaped wall 63, is provided with a liquid level gauge 64, and a discharge duct 65 arranged to project into an opening 200 in the end wall 180 (see particularly Fig. 3). This container is adapted to hold say water, various therapeutic agents commonly used in this art, or a mixture thereof.

As shown in Figures 1 and 2, the opening 200 is provided with a duct 65' into which the discharge end of the conduit 65 projects. The conduit 65 can be closed by a hingedly mounted door 66 which is connected by means of a cable or chain 68 to a lever 67 pivotally mounted intermediate its ends and arranged to be engaged by the top door 9 when it is closed so as to open the damper 66 and to permit the damper 66 to fully

close when the top door 9 is open, as illustrated by Figures 1 and 2. Thus the opening 200 and the end of the conduit 65 can be closed when desired, cutting off the flow of heated air around the container 62 as well as from that container, through the opening 200 into the main cabinet.

As shown in Figures 3 and 4, hot and cold water pipe connections 69 and 70 are provided which extend to a mixing valve 71 from which a line 72, including the hand valve 73 extends to the interior of the cabinet (see Figs. 2 and 3). The pipe extends about halfway into the cabinet and is fixedly mounted therein. It is attached by means of a flexible hose 74 with adjustable spray head 75 depending from a slide 76 which is slidably mounted on a rod 77 extending longitudinally of the cabinet. By this arrangement it is possible to spray or shower a person lying in the cabinet with water at any desired temperature. The spray head 75 may be slid back and forth, as indicated in Figure 2, to cover the entire length of the person's body. Pipe 69 is provided with a branch 74' with hand valve 75' so that fresh water may be added to container 62, see Fig. 3.

Mounted on the end wall 180 is a control cabinet 78 provided with control switches 79, 80 and 81 and the related signal lamps 82, 83 and 84. By way of example, switch 79 may control the electric heater 61, and when that heater is energized the lamp 82 will be illuminated. Switch 80 controls the motor 38 (see Fig. 1) which operates the flexible shaft, and when it is energized lamp 83 will be illuminated. Switch 81 controls the blower motor 48, and when it is energized lamp 84 will be illuminated. The compartment 100 below the control box 78 is simply a connection box to which the various switch leads are taken for proper interconnection.

At 85 is a thermostatic device from which the conductor cable 88 extends to the connection box 100 for controlling the operation of the circulating motor 88. Within the cabinet, as shown in Figure 2, is the thermostat bulb 87 which is connected by means of a capillary tube 86 to the thermostat control as shown in Figure 3. Thermostatic control devices of this type are well known in the art in many forms and the details thereof need not therefore be further illustrated.

Although the operation of the above structure has been indicated by the above description, a little further explanation may be helpful. A person to be treated lies on the mattress M on the removable tray or platform 30 with his head projecting through the opening 4' so as to lie on the headrest 24. The door 22 is slid down around his neck and a towel supported from the bar 22' (see Fig. 6) is draped over his neck. The doors 9 and 10 are closed so that the cabinet is then substantially sealed except for the ventilating window 23 which can be variously positioned to provide ventilation as required within the cabinet. The switch 79 is operated to energize the heater 61, it being assumed that container 62 with a suitable liquid in it is mounted in the rack 60. Door 46 for cabinet 45 is closed. Switch 81 is operated to energize the motor 48 which drives the blower 49. Crank 59 is operated to close the flap valve 55 so that air is circulated from the cabinet into duct 52, branch 53, blower 49, conduit 50, pipe 51 through the housing 45 and into the main cabinet through the duct 65. The damper 66 will be open since, as previously explained, when door 9 is closed it is raised. It will be understood that the valve 55 is in the conduit 54, at a point beyond the branch connection 51, so that when valve 55 75

is closed branch 54, which connects to the container 56, will be closed off. The air in passing upwardly through the compartment 45 and to the duct 65 will pick up vapors from the fluid in container 62, which is heated by the electrical heater 61. These vapors are withdrawn from the container 62 through the opening at the apex of the funnel-shaped top 63 and the end of conduit 65 to mix with heated air passing upwardly through cabinet 45 around the container 62. This mixture passes through opening 200 into the cabinet. With the apparatus operating under these conditions it will be seen that the atmosphere of the main cabinet is circulated and re-circulated passing once on each round trip through the space formed by the housing 45 so as to be reheated by the heater 61 and so as to pick up additional vapors from the heated container 62. Additional water can be added to the container 62 from the connection 69 through the branch 74 when the valve 75 is opened.

Any condensate in the main cabinet and any perspiration given off by the person being treated can drain onto the bottom wall 5 of the main cabinet and pass out through the trapped connection 33. As previously mentioned, the vapors may circulate downwardly around the platform 30, as well as through the large openures 30a. If the atmosphere within the main cabinet becomes too high in temperature notwithstanding the adjustment of the ventilating door 23, the thermostatic device 85 will be actuated to shut off the circulating motor 48.

At the end of this phase of the treatment flap 35 35 valve 55 will be operated through crank 59 and link 58 to bypass the atmosphere being circulated by the blower 49 into branch 54 and from there into the container 56. These gases and vapors are discharged into the container 56 tangentially so that any moisture content is separated from the vapors by centrifugal force and collected in the container while the gaseous constituents escape through the funnel 57.

Doors 9 and 10 may then be opened and the 45 patient may be sprayed or showered by means of the spray head 75. As previously explained, the temperature of the spray water can be controlled by the mixing valve 71. The water, of course, can drain out through the trapped connection 33 to waste. If the patient is to be massaged motor 38 will be energized setting the flexible shaft 43 in operation. Any suitable massage instrument may be detachably mounted on the flexible shaft and the operator may then massage the muscles of the patient as required.

From the above description it will be seen that with this single unit all of the various treatments and manipulations used in this art may be speedily and efficiently carried out under most comfortable conditions for the patient.

It will be apparent from the above description of the single embodiment herein disclosed that many of the details thereof are subjected to variation without departure from the novel combinations of this invention, and I do not therefore desire to be strictly limited to the details of the illustrative example herein disclosed, but only as required by the claims granted me.

What is claimed is:

70 1. An apparatus for the therapeutical treatment of a person in a prone position including a cabinet, having at least one access door forming an enclosure, a conduit connecting with said enclosure at the bottom and top of said cabinet, blower means connected in said conduit for caus-

ing positive circulation of air from said enclosure at the bottom and into said enclosure at the top, heated vapor generating means disposed in said conduit so that the air flow therein picks up said vapors and carries them into said enclosure, a receptacle, a branch connection from said conduit between said blower means and said generating means to said receptacle, a valve in said branch connection, and a central apertured conical cover for said receptacle extending thereinto.

2. In the combination of claim 1, said last means including a damper for controlling the induction end of said conduit, and lever means actuated by the movement of said access door, to cause the damper to close when said door is opened.

3. In the combination of claim 1, said heated vapor generating means consisting of heating means within said conduit, a fluid container in said conduit in heat exchange relation with said heating means, and a connection arranged to cause the withdrawal of vapors generated in said container into the air stream by its flow in said conduit.

4. In the combination of claim 1, a flexible shaft mounted in said cabinet, driving means for said flexible shaft mounted below said cabinet and connected to it, and means within said cabinet for resiliently supporting the end of said flexible shaft to permit manipulation thereof within the cabinet.

HUGO R. SWANSON.
